[57] CLAIM

The ornamental design for adaptable beverage holder, as shown and described.

DESCRIPTION

FIG. 1 is a perspective view as seen from the top front and one side of an “adaptable beverage holder” showing my new design;

FIG. 2 is a view in front elevation;

FIG. 3 is a view in right elevation;

FIG. 4 is a view in back elevation;

FIG. 5 is a view in left elevation;

FIG. 6 is a view in top plan;

FIG. 7 is a view in bottom plan; and,

FIG. 8 is a cross-sectional view thereof taken along line 8—8 of FIG. 3.

The rim and the junction area of the upper portion and lower portion are shaded to show a different texture from the rest of the holder.
